UNITED STATES PATENT OFFICE

120,783

DESIGN FOR A PAPER-TOWEL DISPENSER

Harry E. Houghton, Bronxville, N. Y., assignor to Brown Company, Berlin, N. H., a corporation of Maine

Application March 30, 1940, Serial No. 91,360

Term of patent 7 years

To all whom it may concern:

Be it known that I, Harry E. Houghton, a citizen of the Dominion of Canada, residing at Bronxville, in the county of Westchester and State of New York, have invented a new, original, and ornamental Design for a Paper-Towel Dispenser, of which the following is a specification, reference being had to the accompanying drawing, forming part thereof, wherein

Fig. 1 is a perspective view of a paper-towel dispenser showing my new design; and

Fig. 2 is a bottom plan view of such dispenser.

I claim:

The ornamental design for a paper-towel dispenser, substantially as shown.

HARRY E. HOUGHTON.
